UNITED STATES PATENT OFFICE

2,595,938

PUZZLE AND GAME

Casper E. Grant, Richmond, Va.

Application February 10, 1949, Serial No. 75,629

1 Claim. (Cl. 273—132)

1

This invention relates to puzzles or games, the primary object of the invention being to provide a puzzle which may be played as a game, and one that may be played by a single player in the nature of solitaire.

An important object of the invention is to provide a puzzle wherein there is no set rule for completing or mastering the puzzle, each player using his personal technique, resulting in a highly stimulated mental condition and nerve quieting medium.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing:

Figure 1 is an elevational view illustrating the puzzle or game board, with the puzzle pieces as positioned on one of the standards or posts of the board.

Fig. 2 is a plan view thereof.

Fig. 3 is a sectional view taken on the line 3—3 of Fig. 1.

Fig. 4 is a bottom perspective view of one of the puzzle pieces, illustrating the construction of the opening of the puzzle piece.

Referring to the drawing in detail, the reference character 5 indicates the board of the puzzle or base piece, and the reference characters A, B and C indicate the standards or posts which are secured thereto in spaced relation with respect to each other, the standards or posts being square in cross section, for purposes to be hereinafter more fully described.

The game or puzzle pieces are numbered 1 to 7, and when properly arranged one upon another to form a true object of truncated pyramid construction, the game or puzzle pieces are arranged consecutively on the post A. While I have shown the game pieces as seven in number, it is to be noted that the number of game or puzzle pieces, and size of the member, may be varied to meet various requirements.

When using the puzzle, the object is to move all the game pieces from the post A to the post B, or C without moving two game or puzzle pieces at any one time, or placing a larger game or puzzle piece on a smaller game or puzzle piece at any one time.

In mastering the puzzle the following move-

ments may be followed and when completed, all of the game or puzzle pieces will be arranged on the post or standard C in consecutive order starting with number 1, the game or puzzle piece at the bottom.

7 on C	6 on B	7 on B

These game pieces in the present showing, are rectangular in formation, and vary in size from a large game piece at the bottom of the post, to a small game piece at the top of the post, the outer edges of the game pieces being beveled on

their four sides, so that when the game pieces are arranged or superposed, the game pieces will form an object of truncated pyramid construction.

Each game piece is provided with a central opening 8, the walls thereof being beveled, as clearly shown by Fig. 3 of the drawing, so that when a game piece is positioned with the opening contacting the outer end of a post, the game piece will be centered with respect to the post. The openings 8 are square so that they fit snugly over the post to hold it against movement.

Formed in the upper end of each post are grooves 9 to accommodate the spring clip 10, which when inserted in the grooves, contact the uppermost puzzle or game piece 7, holding the puzzle or game pieces securely on the posts.

Having thus described the invention, what is claimed is:

A puzzle of the class described, comprising a base, a plurality of posts rising from the base, said posts being rectangular in formation, a plurality of puzzle pieces having rectangular openings formed centrally thereof, the openings being wide at their lower ends and tapered inwardly towards their upper ends, the tapered portions of the openings extending throughout substantially the entire thicknesses of the puzzle pieces, substantially small portions of the walls of said openings at their upper ends being vertical, said openings being fitted over the posts, the vertical

sections of the walls of the openings contacting the posts and preventing rotation of the puzzle pieces, said wide portions of the openings guiding the puzzle pieces onto the posts, said posts having horizontal grooves in opposite edges thereof, a spring clip extending through the grooves and engaging the uppermost puzzle pieces on the posts, normally securing the puzzle pieces against displacement from the posts, and the outer surfaces of said puzzle pieces being inclined towards the upper surfaces thereof, providing an object of truncated pyramid shape when the puzzle pieces are properly placed, one upon another on a post.

CASPER E. GRANT.
